UNITED STATES PATENT OFFICE.

EDWIN PUTNAM, OF NEWARK, NEW JERSEY, AND JOHN KIRSCHBAUM, OF WATERBURY, CONNECTICUT.

DESIGN FOR A HOLDER FOR CIGAR-ASHES, &c.

SPECIFICATION forming part of Design No. 17,296, dated May 3, 1887.

Application filed March 21, 1887. Serial No. 232,333. Term of patent 3½ years

To all whom it may concern:

Be it known that we, EDWIN PUTNAM, of Newark, in the State of New Jersey, and JOHN KIRSCHBAUM, of Waterbury, in the State of Connecticut, have invented and produced a new Design for Holders for Cigar-Ashes, Bottles, &c., of which the following is a specification.

In the photograph, Figures 1 and 2 represent the holders from different directions.

The general shape of this holder for cigar-ashes, bottles, &c., is cylindrical and upright, as shown, and the upper open end is higher at one side than the other. The surface of the cylinder is ornamented with parallel channels *a*, producing an appearance of staves, and there are projections at *c* representing nails. The upper ends of the representations of staves are square and one rising above the next, as shown in the photographs, so as to produce an appearance similar to ascending and de-

scending steps. This gives an artistic and pleasing effect to the holder. The surface of the representations of staves may be plain or more or less roughened, as shown, as this does not form part of the present design.

We claim—

The design of the holder for cigar-ashes, bottles, &c., consisting of the design of the vertical cylinder with parallel grooves in its surface, in imitation of staves, and with the upper edge a series of imitations of ascending and descending steps, substantially as represented.

Signed by us this 18th day of March, A. D. 35 1887.

EDWIN PUTNAM.
JOHN KIRSCHBAUM.
